UNITED STATES PATENT OFFICE.

GEORGE H. LOBER, OF TOLEDO, OHIO, ASSIGNOR TO THE BECK-FROST CORPORATION, OF DETROIT, MICHIGAN, A CORPORATION OF MICHIGAN.

RADIATOR.

Application filed June 9, 1926. Serial No. 114,706.

My invention has for its object to form a radiator for automobiles which is so constructed that it will not only sufficiently cool the water that is caused to flow by convection or by pump from the automobile jacket to the radiator, but also to sub-divide the stream of water and direct it through a plurality of tubes that are of sufficient size to conduct the water through the radiator and yet are expandible in size to give room for the expansion of the water when the temperature lowers sufficient to cause the water to freeze and thus prevent tearing of the tubes by the freezing of the water. The radiator is also so constructed that when the ice melts, the tubes will be caused to return to their normal size so that in subsequent freezing of the water, the tubes may be again expanded and distend to allow for the increased volume without tearing of the tubes.

My invention particularly provides an efficient means for permitting the expansion of the tubes and causes their return to their normal size when their distension ceases. The invention may be contained in radiators which vary in their details of construction and to illustrate a practical application of the invention, I have selected a radiator containing the invention as an example of such structures and shall describe it hereinafter. The radiator selected as an illustration of such construction is shown in the accompanying drawings, and is described hereinafter.

Figure 1 of the drawing illustrates a radiator of the type to which my invention is applied. Fig. 2 illustrates a part of the radiator. Fig. 3 illustrates a strip having protruding ribs that elastically engage two side walls of two parallel water passage-

ways, and at the same time forms a heat conducting means for transferring the heat of the water to the air that passes through the strip and makes contact with the strip. Fig. 4 illustrates the form of the separating strip at a completion of a step in the process of producing it. Fig. 5 is a view of a section of a part of the radiator, the plane of the section extending transversely to the water tubes. Fig. 6 is an edge view of the strip shown on Fig. 3.

As is well known in connection with automobiles, the radiators commonly used are of the type shown in Fig. 1, which have a

"honey-comb" face 1, that are formed by corrugating angularly the edge portions of the strips that form the water tubes of the radiator and a spacer for spacing the water tubes. The honey-comb face which is located not only in the front of the radiator, but also at the rear of the radiator affords a means for rigidly holding the water tubes in position and in spaced relation to allow the air to move between the tubes. The tubes are formed usually of pairs of sheet metal strips having their edge portions corrugated and secured together by solder. Soldering of the edges of the tube is usually done by dipping the corrugated edge portions in solder. The portions of the pairs of strip between the corrugated edges are so shaped that they will normally be substantially parallel to each other and in spaced relation so as to form a thin column or film of water within the tube and give a large contact area for the conduction of the heat from the water. The tubes communicate with the chamber that is located at the top 2 of the radiator and also a chamber that is located at the bottom of the radiator. The upper chamber of the radiator connects with the upper portion of the jacket of the engine of the automobile while the lower chamber connects with the lower portion of the jacket. My invention provides a separating strip which is so constructed as to make contact with the air streams through the radiator and form a large area of contact with the strips that form the tubes of the radiator and at the same time permit distension of the tubes and elastically cause the return of the tubes to their normal size when the cause of distension is removed.

As shown in Fig. 5, the tubes are formed of the strips 3 and 4, having corrugated edged portions 5. The corrugated edge portions of the strips 3 and 4 are nested one within the other and soldered by dipping or otherwise to seal the rear and front edges of the tubes that is thus formed. The strips 3 and 4 are pressed to shape so that when the edges are thus nested together the body portions of the strip will be located in parallel and spaced relation relative to each other, as shown in the figure. In the form of construction shown in the drawings the strips 3 and 4 are preferably provided with central

beads 6 that extend inward with respect to the tube and so as to maintain the body portions of the strips in their parallel relation notwithstanding exterior pressure that may be brought to bear on the tubes by the separating strip shown in Fig. 3.

- Juxtaposed tubes are separated by the strip 7, which has corrugated edged portions 8, and is so placed relative to adjoining tubes 10 that the angles of the corrugations make contact with the angles of the corrugations of the tubes. This forms the "honey-comb" construction or appearance at the front and at the rear of the radiator and produces 15 spaces through which the air may enter and leave the radiator and pass between the tubes while the heat of the water is being conveyed through the walls of the tubes to the relatively moving air. The separating 20 strips and the tubes are secured in their relative positions by soldering. Usually the strips are mechanically secured or bound together and are dipped in solder. The solder then maintains the parts in their relative 25 positions when in use.

The strips 7, in the process of their formation are die pressed to form channels as shown in Fig. 4. They are then split cross-wise through the central portions thereof 30 and parts between these slits are struck up which results in the formation of a plurality of ribs 9, the adjoining ribs, except at their ends being displaced by a distance substantially equal to twice the depth of the 35 corrugations 8, formed along the edges of the strips 7. The central parts of the ribs 9 are provided with beads 10, that operate to stiffen the central parts of the ribs leaving the end portions 11, elastic to elastically 40 maintain the ribs in their normal positions. When the strips 7 are in position between the vertical water tubes, the ribs 9 are placed against the straight vertical walls of the adjoining water tubes on opposite sides of the beads, 10, which project inward with respect to the ribs of the strips. Thus on opposite sides of the beads 10, each 45 rib is, in the assembly of the strips in forming the radiator, placed in intimate contact with one of the heat conductive walls of a tube. The ribs thus operate normally to press the walls of each tube towards each other and by reason of the elastic portions of the ends of the ribs, elastically hold the 50 tubes in their parallel relation. To produce a limitation of this inward movement of the tubes of the radiator, the beads on the walls of the tubes are held in contact by the pressure of the ribs, the beads however, maintaining the body portions of the walls of each tube in spaced relation, permitting the 55 free flow of water through each tube and yet form a relatively thin column or film of water within the tube from which the heat 60 may be readily conveyed.

The elastic end portions 11, of the ribs 9, are located in line with angles 13 of the corrugations of the edges of the strips 7, and consequently the air as it moves relative to the radiator through the openings formed 70 by the corrugations, strike the metal of the edge portions where the elastic parts 11, join the edge portions. The air also directly strikes the end portions 11, with the results that the heat conducted from the walls of the radiator tubes to the ribs is immediately removed by the moving air. The spacing ribs maintain a relatively large space between the tubes of the radiator which gives opportunity for the air to receive the heat 80 of the water through the walls of the tubes, the air being moved rearwardly by the in-rushing air through the openings formed in the front of the radiator.

I claim:

1. In a radiator for an automobile, a plurality of vertical water tubes formed by pairs of strips of sheet metal located in spaced relation and having corrugating contacting edges, the strips forming the tubes having inwardly extending beads located along the vertical central lines of the strips, beads of each tube being normally in contact with each other and adapted to be separated from each other by freezing of the water in the tube, spacing strips located intermediate the tubes and having corrugated edges, the angles in the corrugations of the spacing strips being in contact with the angles of the corrugations of the tubes to form air passage-ways between the tubes, each spacing strip having a plurality of alternately projecting ribs struck up between the corrugated edge portions and pressed against the tubes and extending transversely substantially the width of the tubes, the end portions of the ribs being elastic for elastically pressing the sheet metal strips of the tubes towards each other, the beads of the tubes operating to limit the inward movement of the strips of the tubes by the pressure of the ribs when the ice thaws.

2. In a radiator for an automobile, a plurality of vertical water tubes formed by pairs of strips of sheet metal located in spaced relation and having corrugated contacting edges, the strips of sheet metal having central beads being normally in contact with each other and adapted to be separated from each other by freezing of the water in the tubes, spacing strips being located intermediate the tubes and having corrugated edges, the angles in the corrugations of the spacing strips being in contact with the angles of the corrugations of the tubes to form air passage-ways between the tubes, each spacing strip having a plurality of elastic portions struck up and located transversely in contact with substantially the entire width of the tubes, the end portions of the

said struck up portions being formed of elastic sheet metal, while the central portions of the said struck up portions are beaded to increase the rigidity of the central portion, whereby the tubes will be elastically pressed by the elastic ends of the struck up portions located on opposite sides of the

tubes to yieldingly resist the expansion when the water freezes and to cause the tube to return to its normal condition when the ice thaws.

In testimony whereof I have hereunto signed my name to this specification.

GEORGE H. LOBER.
